UNITED STATES PATENT OFFICE.

WILLIAM H. GRIFFIN AND FRANK ILLINGWORTH, OF FITCHBURG, MASSACHUSETTS.

CAP FOR TANKS.

Application filed October 6, 1922. Serial No. 592,762.

To all whom it may concern:

Be it known that we, WILLIAM H. GRIFFIN and FRANK ILLINGWORTH, both citizens of the United States, residing at Fitchburg, in 5 the county of Worcester and State of Massachusetts, have invented a new and useful Cap for Tanks, of which the following is a specification.

This invention relates to a cap adapted to 10 be applied to a gasoline, water or other tank that has to be filled at intervals and the particular objects thereof are to provide a simple and convenient mechanism whereby the tank can be opened to permit filling or the 15 like and readily closed again in a positive manner so that it will not open by accident.

The invention also involves improvements in the details of construction of the means by which the cap is held in closed position on 20 its seat yieldingly and yet positively prevented from being opened and in the way of supporting the closing disc itself.

Further objects and advantages of the invention will appear hereinafter.

25 Fig. 1 is a plan of a cap cover constructed in accordance with this invention and shown in open position in dotted lines;

Fig. 2 is a central sectional view of the same shown in closed position; and

30 Fig. 3 is an end view thereof.

Fig. 4 is a cross sectional view of the cap in inoperative position.

Although capable of general use, this invention is particularly adapted for application 35 to the gasoline tank of an automobile and for that purpose we have shown it as applied to a cover 10 having an internal screw thread and adapted to be screwed on the usual threaded inlet of a gasoline tank, 40 but it will be understood that the invention is capable of use with other types of covers. This cover is shown as provided with an opening 11 through which the tank 12 below can be filled.

45 On this cover also is a guide 13 having a horizontal upper surface preferably and a stop 14, a space 15 being provided between these two elements 13 and 14. The opening 11 is provided with a raised seat 16 surrounding it. At the side of this seat opposite the space 15 there is an integral projection 20 having a cam surface 21 arranged at

an inclination for a purpose to be described and provided with an inclined flat top surface 22. From the center of this projection 55 extends a bolt 23 or the like having a head. Under this head there is a spring 24 surrounding the bolt and resting on the upper surface of a closing lever 25 which is pivotally mounted on the bolt 23. This lever has 60 at its end beyond the pivot a projection 26, the lower surface of which is of cam shape and pitched at the same angle as the cam surface 21. The bottom of the lever 25 is adapted to rest on the inclined surface 22 65 when not forced away from the same in a manner to be described.

This lever is provided with a projection 28 which is employed as a handle. At a point that is central with respect to the 70 opening 11, when the device is closed, it is provided with an opening 29. In this opening there is a bushing 30 surrounding a screw 31 with a loose fit. This screw is integral with a cap 32 preferably or at least 75 fixedly connected therewith. This cap has a packing 33 around its edge and is adapted to rest on the seat 16 to close the same. A nut 34 on the top of the lever 25 screws up 80 on the screw 31 and holds the cap 32 in place on the lever. The bushing 30 is arranged to have a length greater than the thickness of the lever at that point so that the nut 34 will screw down on top of the bushing and leave the cap 32 somewhat loose in position 85 on the lever and capable of turning thereon.

In the operation of the device, the cover 10 is intended to be permanently screwed on the threaded inlet of the tank 12. It is not meant by this that it is impossible to take it off but simply that it is not intended to take it off each time the tank is filled. When the tank is filled through the opening 11 the cap is in the position shown in dotted lines in Fig. 1. It is closed simply by swinging the handle around to the full line position in Fig. 1. This cap has a surface 35 which is adapted to rest on top of the guide 13 while the cap is being closed. It will be observed also that the two cam surfaces 21 and 26 co-act with each other during the closing of the cap to force the lever at that end upwardly against the action of the spring 24. This spaces the lever farther from the top of

the cover than when it is open and insures that it will be perfectly simple and easy to bring the cap 32 over the cover into the place for closing. It is spaced from the 5 same by the movement of the lever caused by the two cam surfaces. At the same time the handle end of the lever is held up by the surface 13 so that the cap 32 is not in contact with its seat until the instant of closing 10 which occurs when the lever slips off the surface 13 into the space 15. When this occurs the two cams 21 and 26 are at their extreme positions exerting the maximum pressure on the spring and the spring is acting 15 on the surface of the lever to force the same down about the two cam surfaces 21 and 25 as a fulcrum. The space 15 is deep enough so that it does not afford any opposition to this action and the lever then is 20 pressed down by the spring so it rests on top of the cap which forces the cap firmly into contact with the open seat on the cover.

When it is desired to open the tank, the 25 lever is first forced upwardly against the action of the spring. This raises the lever out of contact with the cap and into contact with the nut and finally through the action of the nut 34 raises the cap upwardly directly off its seat. The operator 30 then moves the lever off to the right so that its bottom will rest on the surface 13. Although it is natural for him to push it around the rest of the way, even if he did not, the cam surfaces 21 and 26 would 35 act to move it around and open the cover so that the tank can be filled.

A casing 40 surrounds the spring under the head of the bolt 23. It is cut out to receive the lever and turns with it. The 40 surface 22 is inclined to lift the lever off the top of the surface 13 as it swings away.

It will be seen therefore that by this arrangement we have provided an inexpensive and accurately working device for the 45 purpose intended which securely seals the tank when closed and can be opened readily and without unscrewing the cover and also without injuring any screw threads or other elements required for keeping the 50 cover closed. If the parts become worn very much in practice, the screw 23 can be screwed down a little more to increase the resistance of the spring 24, thus overcoming any wear that may take place.

55 Although we have illustrated and described only a single form of the invention and referred to its use especially for only one particular kind of a tank closure, we are aware of the fact that it is capable 60 for general use and that modifications can be made in the details of construction without departing from the scope of the invention as expressed in the claims. Therefore we do not wish to be limited to all 65 the details of construction herein shown

and described or to its use for a gasoline tank for an automobile, but what we do claim is:—

1. In a tank closure, the combination of a cover having an opening therethrough provided with a seat on the top thereof, with a cap adapted to rest on the top of said seat, a lever on which said cap is freely and movably supported, a guide for the free end of said lever located on the 70 cover, and yielding means for forcing said lever down to engage the cap and hold it in position to seal the opening in the cover.

2. In a tank closure, the combination with a cover having an opening therethrough provided with a seat on the top thereof, of a cap adapted to rest on the top of said seat and having a screw extending upwardly therefrom, a lever having a passage for said screw, a guide for the free end of said lever located on the cover, yielding means for forcing said lever down in the cover, a bushing in the passage surrounding the screw and of a length greater than the thickness of said lever, and a nut on the top of the lever adapted to be screwed down on said bushing for holding the cap on the lever in a position to turn and move thereon.

3. In a tank closure, the combination with a cover having an opening therethrough provided with a seat on the top thereof, of a cap adapted to rest on the top of said seat, a lever on which said cap is freely and movably supported, a guide for the free end of said lever located on the cover, yielding means for forcing said lever down to engage the cap and hold it in position to seal the opening in the cover, and positive means for forcing upwardly the end of said lever opposite said guide, the yielding means being located between the positive means and the cap.

4. In a closure for a tank, the combination of a cover on the tank having an opening therethrough provided with a seat on the top of said opening, with a lever pivoted on said cover, a cap adapted to rest on said seat and movably supported by said lever, a guide on the cover for the free end of said lever, a spring for forcing the lever downwardly toward the cap, said cover and lever having a pair of co-acting cam surfaces at a point beyond the spring for forcing the lever upwardly at that end to compress the spring and hold the lever down at the other end against the cap.

5. In a closure for a tank, the combination with a cover on the tank having an opening therethrough provided with a seat on the top of said opening, of a lever pivoted on said cover, near one side, a cap adapted to rest on said seat movably supported under said lever, a guide on the cover opposite the pivot of the lever for the 125

free end of said lever, a spring surrounding the pivot for forcing the lever downwardly toward the cap, said cover and lever having a pair of co-acting cam surfaces at a point beyond the pivot on which the lever is mounted for forcing the lever upwardly at that end and downwardly at the other to hold the lever down against the cap under the force of said spring. In testimony whereof we have hereunto affixed our signatures.

FRANK ILLINGWORTH.
WILLIAM H. GRIFFIN.
